UNITED STATES PATENT OFFICE.

STANLEY B. ASHFORD, OF MADDOCK, NORTH DAKOTA.

WASHBASIN CONSTRUCTION.

Application filed May 9, 1923. Serial No. 637,774.

To all whom it may concern:

Be it known that I, STANLEY B. ASHFORD, a citizen of the United States, residing at Maddock, in the county of Benson and State of North Dakota, have invented 5 certain new and useful Improvements in Washbasin Constructions, of which the following is a specification.

This invention relates to improvements 10 in wash basins or analogous receptacles, and is particularly directed to improvements in the control of drain valves thereof.

The primary object of this invention is 15 the provision of valve means for controlling the maintenance of water within or the drain of water from a basin embodying novel valve features which will permit of the drain of water in convenient manner and without the necessity of reaching into the 20 water to remove a drain plug.

A further object of this invention is the provision of drain valve control means for receptacles, such as wash basins, and which will afford a convenient, practical, relatively simple and positive feature of valve 25 regulation, which may be effected exteriorly of the basin, and which may be so constructed as to dispense with the necessity of providing an overflow in the basin.

Other objects and advantages of this 30 invention will be apparent during the course of the following detailed description.

In the accompanying drawings, forming 35 a part of this specification, and wherein similar reference characters designate corresponding parts throughout the several views.

Figure 1 is a cross sectional view, taken 40 through the basin and the drain fitting connected thereto, showing more particularly the improved drain valve or plug as used in connection therewith.

Figure 2 is a cross sectional view, taken 45 through the valve adjusting means.

Figure 3 is a fragmentary view, partly 50 in section, showing details of the construction of the valve means.

In the drawings, wherein for the purpose of illustration is shown but the preferred embodiment of this invention, the letter A may generally designate a basin or other receptacle, in connection with which a drain fitting B may be used, and having associated therewith means C em-

bodying a control valve, and means for 55 controlling the same.

Referring to the construction of the fitting B, the same preferably comprises an outlet extension 10, providing a passageway 11 therethrough, and which is adapted 60 for disposal within the passageway 12 of a basin extension 13 as to depend from the basin. The upper end 14 may be suitably flanged, as illustrated in Figures 1 and 4 of the drawings, and attached at the inner surface of the basin about the opening 12 therein. The exterior screw threads 15 are annularly provided about the outlet extension 10 immediately below the lower surface of the basin projection 13, adapted 70 for detachably receiving the enlarged valve or drain chamber 16 as through a screw threaded opening 17 inwardly of the top thereof, and whereby the reduced lower portion of the outlet extension 10 may depend 75 into the enlarged chamber 18 provided by the drain casing or housing 16. A packing 20 of any approved construction may be provided intermediate the facing surfaces of the basin projections 13 and the top of the casing 16 to provide a leak proof connection.

The depending end of the outlet extension extends axially inwardly of the top 85 of the casing 16, in spaced relation to the inner surfaces of the casing 16 and for a distance approximately one-half the length of the chamber 18. The lower end of the outlet 10 is, of course, open and adapted for receiving the valve head 25 for cooperation 90 thereagainst, as will be subsequently described. The enlarged chamber 18 of the drain casing 16 thus not only extends below the drain outlet 10 but upwardly circumferentially thereabout. The casing 95 16, at its lower end, may provide a reduced annular exteriorly screw threaded neck 27, adapted for detachably receiving a packing and clamping nut construction 28 whereby the ordinary drain conduit 29 may be 100 clamped thereto to provide a leak proof connection, substantially as is illustrated in Figure 1 of the drawings.

Referring to the means C for the regulation of water in the basin A, the same 105 preferably includes the valve head 25, which may be cup shaped, providing a recess 30 inwardly of the top thereof for detachably

receiving a packing strip or washer 31 in detachable manner, as by attachment to the valve head 25, by means of a detachable screw 32 arranged centrally of said valve head. A shank or stem 37 is preferably rigidly or integrally connected to the valve head 25, extending upwardly from a top marginal edge thereof in a direction at right angles to a plane defined by said valve head, and having the upper end 39 thereof bent at an acute angle thereto and extending for a relatively short distance, being screw threaded, as at 40, upon its free end, substantially as is illustrated in Figure 3 of the drawings.

The means C also includes an operating rod 42, which is provided at an end thereof with an enlarged ball 44, adapted for pivotal disposition in a socket opening 45 provided 20 in an externally screw threaded extension 46 formed as a part of the drain casing 16, and adapted for pivotal disposition in said socket against liability of displacement by means of a packing nut 50, which is formed 25 to accommodate the operating rod 42, to permit the oscillatory action thereof in a vertical plane. This ball 44 is provided with a screw threaded socket 51, radially inwardly therefrom opposite to the rod 42, 30 for detachably receiving the screw threaded end 40 of the valve stem 39 therein. The operating handle or rod of the valve head 25 is thus observed to be pivoted at a point upon the casing 16, considerably above the outlet end of the part 10 which extends into the drain compartment of the casing 16, and which construction is provided so that drain water will ordinarily flow direct from the drain compartment 18 into the drain conduit 29, without rising to the level of the ball and socket pivot construction of the valve.

In connection with the valve rod 42, novel means 60 is provided as part of the control means C, for maintaining the valve in a predetermined position. This means 60 preferably includes a cylindrical casing or tube 61, which at its upper end may be provided with an annular flange 62, adapted for connection in any approved manner to the bottom surface 63 of the annular basin flange 64, so that said tube or casing 61 may vertically depend at the side of the basin A, substantially as is illustrated in Figure 1 of the drawings. The valve handle 42 extends in an irregular formation from its pivot end to the casing 61, and extends into said casing through slots 63 which are provided longitudinally therein at diametrically opposed sides. These slots 63 extend from the detachable bottom 64 of the casing 61 upwardly along the tubular casing, so as to permit the movement of the valve rod 42 at its free end, in a vertical plane. A spiral compression spring 67 is provided

within the compartment of the tubular casing 61, engaging the top of the casing at one end and at its other end engaging the free end of the valve rod 42 to normally maintain the valve rod in abutment with the detachable bottom or cap 64 above mentioned, and in which position the valve head 25 closes the passageway 11 of the outlet extension 10 so that water will be maintained in position within the basin A.

A novel latch member 70 is resiliently attached to the casing 61, for regulating the valve and its valve rod as to position. This latch member 70 includes a portion 71, which is attached at its lower end exteriorly upon the casing 61 and at its upper end yieldably extends through an opening 72 into the compartment of the tubular casing 61. The latch 70 also includes a substantially horizontal finger engaging portion 74, integral with the portion 71 at the end of the latter which extends into the casing 61, and which lies for the most part exteriorly of the casing 61, whereby a person by placing his or her finger therebeneath and drawing upwardly or outwardly may flex the latch 70 as to entirely withdraw the same from the opening 72.

Referring to the operation of the valve mechanism of this invention, if it is the desire of a person to run a quantity of water into the basin A, the latch member 70 is drawn outwardly, as above mentioned, so that the spring 67, normally under compression, operates upon the valve rod 42 and moves the same into the position illustrated in Figure 2 of the drawings for closing the valve 25 over the outlet end of the extension pipe 10, and whereby water may be suspended in the basin compartment. It is to be noted that when in this closed position, the inwardly extending end of the latch member 70 is disposed transversely between adjacent convolutions of the spring 67, intermediate its ends, so that a portion 67^a of the spring, intermediate the rod 42 and inwardly extending end of the latch 70 is free to be further compressed should the valve rod 42 be further elevated. The compression of this portion 67^a of the spring 67 is sufficient to maintain the valve 25 in closed position under weight of a normal body of water in the basin A. However, if the quantity of water in the basin A becomes excessive and threatens to overflow the top of the basin, the spring portion 67^a incident to the weight of the excessive body of water will be further compressed by action of the valve rod 42 thereagainst, and the body of water will move the valve head 25 open, or out of seating relation with the outlet end of the pipe portion 10, so that a portion of the water may drain out of the basin to prevent overflow therefrom. It is thus obvious that the necessity of providing an

overflow for the basin A is done away with, as this valve action is automatic and will permit but a normal quantity of water to remain in the basin, notwithstanding the flow of water into said basin.

When it is desired to drain the waste water from the basin A, the operator need only pull the latch 70 from the path of the spring 67 and incident to weight of water 10 within the basin A acting upon the valve 25, the valve rod 42 will act upon the spring 67, compressing the same to permit the drain of the water from the basin outlet tube 10 past the valve 25. After the water has been 15 drained from the basin, the spring 67 will automatically close the valve head 25.

From the foregoing description of this invention it is apparent that a wash basin construction has been provided embodying 20 control means for water inlet and outlet with respect thereto, which is practical, positive in operation, sanitary, and which facilitates the handling of waste water.

Various changes in the shape, size and arrangement of parts may be made to the form 25 of invention herein shown and described, without departing from the spirit of the invention or the scope of the claims.

I claim:

- 30 1. In a device of the class described, the combination with a basin, of an outlet tube connected to said basin, a drain conduit receiving the outlet tube therein in spaced relation therewith, a valve for the outlet end of said tube, a valve stem connected to said valve extending upwardly from said valve in the space intermediate the outlet tube and drain conduit for pivotal connection to the conduit at a point above 35 the outlet end of the outlet tube, a rod for operating said valve extending exteriorly of said drain conduit from the pivot point of the valve stem, a spring casing having the outer end portion of said rod slidable longitudinally therein, a spring in said casing normally holding the rod at one end of the casing with the valve closed and a latch entering said spring casing for engaging the spring intermediate the length thereof 40 when the valve is closed and for engaging the rod when the valve is open and retaining the valve in an open position.
  - 45 2. In a device of the class described, the combination with a wash basin having an
- outlet opening therein, a valve for said outlet opening, an operating rod for said valve, a casing reciprocably receiving the movable end of the valve rod therein, a spring in said casing normally under compression to act upon said rod whereby to close the valve, 55 and a latch member carried by the casing adapted either to support said valve rod when the valve is open or cooperate intermediate the ends of the spring whereby the part of said spring intermediate said latch and valve rod may be compressed by an excessive quantity of water within the basin acting upon said valve to open said valve for drain of any excess water in said basin 60 therefrom. 70
3. In a device of the class described, the combination of a basin, of an outlet tube connected to the basin, a drain casing receiving the outlet tube therein, a valve for the outlet tube, a valve stem carried by the 75 valve and extending upwardly therefrom within the drain casing for pivotal connection to the casing at a point upwardly of the outlet end of said outlet tube, an operating rod exteriorly of said drain casing for movement of said valve and valve stem, a cylindrical shaped casing attached at an outer edge of said basin and having a slot therein into which the free moving end of said operating rod extends, a spring under compression operating within said cylindrical casing and upon the free end of said operating rod to normally urge said rod into such position that the valve will be closed 80 against said outlet tube, a latch member resiliently connected to said spring casing having an end thereof normally entering said casing whereby the same may receive the free end of the operating rod thereon to suspend the valve in open position, said latch being adapted for manual operation whereby the compression spring may move said operating rod for closing the valve, said latch upon being released when the valve is closed entering said spring casing whereby 85 90 95 but a short length of said spring intermediate the latch and the operating rod is free to be compressed under weight of excess quantity of water within the basin to open the valve for flow of any excess water from 100 105 said basin.

STANLEY B. ASHFORD.
